DESK BASE FOR WRITING INSTRUMENTS

Donald W. Doman, Janesville, Wis., assignor to The Parker Pen Company, Janesville, Wis., a corporation of Wisconsin

Application August 1, 1956, Serial No. 42,478

Term of patent 14 years

(Cl. D74—1)

Fig. 1

Fig. 2

Fig. 3

Fig. 1 is a top plan view of a desk base for writing instruments, showing my new design;

Fig. 2 is a front elevational view of the same;

Fig. 3 is a side elevational view thereof, the dotted line showing of a writing instrument being, for illustrative purposes only; and

Fig. 4 is a front perspective view thereof.

I claim:

The ornamental design for a desk base for writing instruments, substantially as shown.
